(57) **CLAIM**

We claim the ornamental design for a structural member for a rack, as shown and described.

DESCRIPTION

FIG. 1 is a front perspective view of a structural member assembly, showing our new design;

FIG. 2 is a right side elevation view of the structural member assembly;

FIG. 3 is a left side elevation view of the structural member assembly;

FIG. 4 is a rear elevation view of the structural member assembly;

FIG. 5 is a front elevation view showing two faces of the structural member assembly;

FIG. 6 is a rear perspective view of the structural member assembly;

FIG. 7 is a perspective view of a first component of the structural member assembly;

FIG. 8 is a perspective view of a second component of the structural member assembly; and,

FIG. 9 is a top plan view of the structural member assembly of FIG. 1, the opposite bottom plan view being the same as the top plan view.

The broken line showing of environment is for illustrative purposes only and forms no part of the claimed design.
